LAUNDRY MACHINE

James B. Kirby, West Richfield, Ohio, assignor,
by mesne assignments, to The Apex Electrical
Manufacturing Company, Cleveland, Ohio, a
corporation of Ohio, as trustee

Application May 1, 1931, Serial No. 534,316

18 Claims. (Cl. 68—15)

This invention relates to laundry machines and has for its object the provision of a machine combining in itself facilities for washing and centrifugally extracting miscellaneous fabrics in a single container and comprising numerous advantageous features of simplicity, compactness, convenience and successful operation. From the broad aspect this type of laundry apparatus is not new, having been heretofore set forth in considerable part in my previous applications Serial No. 694,899, filed February 25, 1924, which matured on August 7, 1934 into Patent No. 1,969,176, Serial No. 176,908, filed March 21, 1927, which was abandoned on April 3, 1932, Serial No. 191,483, filed May 14, 1927, which matured on May 30, 1933 into Patent No. 1,911,903, and others hereinafter referred to.

The particular objects of the present invention are the provision of a combined washing machine of the oscillating-dasher type and extractor of the centrifugal type, wherein the dasher is entirely disconnected from the driving mechanism during the rotation of the extractor; the provision of a new improved, and simplified, driving mechanism for rotating the centrifuge or oscillating the dasher selectively; the provision of new, improved, and simplified means for effecting mechanical connection and disconnection of the parts and of raising and lowering the container; the provision of a new and improved type of housing for the mechanism; while further objects and advantages of the invention will become apparent as the description proceeds.

In the drawings accompanying and forming a part of this application Fig. 1 is a vertical sectional view through the center of a preferred type of my improved laundry machine showing the parts in washing position; Fig. 2 is a similar view through the same machine, showing the parts partly in elevation and with the container and agitator in extracting position and differing from Fig. 1 in that certain parts to the left of the view are not shown in section; Fig. 3 is a horizontal sectional view corresponding to the line 3—3 of Fig. 1 and looking downwardly; Fig. 4 is a horizontal sectional view corresponding to the broken line 4—4 of Fig. 2 and looking downwardly; Fig. 5 is a detail side elevation of a part of the mechanism shown in Fig. 1; Fig. 6 is a vertical sectional view through a modified form of machine containing my improvements and showing the parts in washing position; Fig. 7 is a similar view of the last named machine showing the parts in extracting position; Fig. 8 is an enlarged detail view of the friction clutch shown in Figs.

6 and 7; Fig. 8a shows certain parts of said friction clutch; and Fig. 9 is a horizontal section on the line 9—9 of Fig. 7 and looking upwardly.

Describing first that form of my improved machine illustrated in Figs. 1, 2, and 3, the same includes an upright casing having a side wall 1 and a bottom 2, resting on a suitable framework, one example of which will presently be described. Secured to the bottom 2 in leak-proof relation is the vertical, hollow, bearing-sleeve 3 which projects above liquid level. Movable surrounding this sleeve is a second sleeve 4 having secured to its lower end the circular bottom 5 of the clothes container. The side wall of this container is made as a surface of revolution coaxial with the sleeve 4 and preferably has outwardly rounded portions 6 and 7 at bottom and top respectively, with a perforated portion 8 between them. The portion 7 terminates in a rolled rim 9 defining a large working opening coaxial with the sleeve 4, and the portion 7 is preferably imperforate for a purpose to be hereafter described. The bottom of the container may be made in any one of many forms, but is preferably made double, as set forth in my Patent No. 1,277,604, granted September 3, 1918, one portion, as that shown at 5a being integral with the portion 5, and the other portion, shown at 10, consisting of a circular metal disk tightly fastened to the sleeve 4 separately from the portion 5a and having its margin rigidly braced and secured to the bottom 5 in stiffening relation.

Movably surrounding the sleeve 4 is a third sleeve 12 having at its lower end a circular disk 13 overlying the bottom of the container, and also having laterally-projecting, liquid-agitating blades 14 located in a position to be immersed in the liquid with which the casing is supplied. This disk 13 is made to flare downwardly and outwardly from its sleeve, and the bottom 5a is caused to rise conically therein the better to prevent the collection of clothes or foreign articles thereunder as set forth in my applications Serial Nos. 694,899, 191,483, above mentioned, and in my application Serial No. 526,076 filed March 28, 1931 for the reissue of my Patent No. 1,741,191, issued December 31, 1929, and which was on December 8, 1931 reissued as Patent No. 18,280.

Journaled inside the sleeve 3 is a hollow shaft 15 having its upper end operatively secured to the sleeve 4 in rotating and supporting relation. In the present embodiment I have shown the sleeve 4 as having an internal flange 16 pinned to this shaft, but this is merely for illustrative purposes. Journaled inside the shaft 15 is a shaft 17

having its upper end suitably formed, as by the flutes 18, for the reception of the sleeve 12 in supported and operated relation, said sleeve being here provided with an internally-fluted socket 19 for the purpose.

5 The sleeve 3 is supported by attachment to a hollow boss 20 carried by the supporting frame which will be described hereafter. Rotatably journaled on the exterior of said sleeve 3 beneath said boss is the hub 21 of a spiral gear 22 which meshes with a companion spiral gear 23 carried by the horizontal drive shaft 24. The position of the gear 22 is fixed on the sleeve by means of a collar 25. Journaled in suitable bearings 30-30 10 carried by the frame is a vertical shaft 31 having at its upper end a spiral gear 32 meshing with a second spiral gear 33 carried by the shaft 24 and having at its lower end a crank 35 connected by a pitman 36 to an oscillatable, toothed member 37 pivoted on a vertical axis at 38.

20 Rigidly secured to the lower end of the shaft 17 is a pinion 40 adapted to mesh with the oscillatable member 37 whereby oscillating movement may be transmitted to the sleeve 12 so long as this 25 meshing exists. Rigidly secured to the lower end of the hollow shaft 15 is the entering element 41 of a cone clutch, the complementary receiving portion of which is a hollow tapering flange 42 integral with and depending from the gear 22 30 whereby rotation may be transmitted to the container 8 so long as these clutch-members remain in contact.

Surrounding the shaft 17 is the bottom-plate 43 of a stirrup 44 having elevated sides 45 to 35 which are articulated the upper ends of connecting links 46, whose lower ends are articulated to the forked arms 47 of a pedal lever 48 which is pivoted to the frame by a horizontal pin or shaft 49. A suitable thrust-bearing is interposed between the stirrup and the next adjacent part 40 above the same, which in this case is the clutch-member 41, the bearing being shown at 50. The extremity of the lever 48 is provided with a corrugated plate 51 for the operator's foot, and near thereto a detent lever 52 is provided having a tooth 53 adapted to engage notches 54 in a stationary sector 55 thus enabling the parts to be retained in selected position.

An electric motor 60 having its armature shaft 50 61 horizontal is pivotally suspended from a horizontal pivot-rod 62 carried by the frame, the rod and shaft being parallel to the shaft 24 and to each other. Motion is transmitted between the shafts by a belt 63 applied to pulleys with which 55 said shafts are provided, the motor being kept tight by means of a spring 64 applied to a portion of said motor remote from the rod 62 and adjustably tightened by a nut 65 and a threaded rod 66 carried by the motor.

60 The operation of the device thus far described is as follows: the clothing to be washed is placed in the container 8 and detergent liquid added to a level preferably between *a* and *b* shown in Fig. 1. With the parts occupying the position shown 65 in Fig. 1, the operation of the motor causes an oscillatory movement of the sleeve 12 its blades 14, setting up vigorous currents inside the container in the direction shown by the arrows. This agitation loosens the dirt from the clothing and to 70 this dirt, together with the scum is largely expelled through the apertures in the sides and to the bottom of the container where they are entrapped, the grit settling to the bottom and the scum collecting in the annular space outside the wall 1. During this part of the action the con-

75 tainer has been free to rotate but does not so rotate unless accidentally something becomes caught between it and the dasher. When the washing operation has continued to a sufficient extent the pedal is depressed bringing the parts into the position shown in Fig. 2. This disengages the pinion 40 from the oscillating member 37 and brings it into engagement with a spring 68 carried by one of the bearings 30 whereby it is held stationary; although it is likewise possible to omit the spring in which event the dasher will either revolve or remain at rest in accordance with the comparative friction effect. Upon engagement of the two parts of the friction clutch 10 the container is gradually brought to a high speed 15 of rotation in order to extract adherent liquid centrifugally. Elevation of the clutch member 42 under the influence of member 41 is opposed by a thrust bearing 66 and spring 67 which thus 20 produces a predetermined driving effect.

Partly as a safety measure, and partly to reduce the cost of the casing, the latter is terminated by a rim 70 located at such level as to be overtopped by at least part of the apertures of the container when said container is elevated, 25 thus necessitating the employment of the removable splash-band 71. Preferably this band is provided with inwardly-turned rim 72 loosely receiving the rim 9 of the container and preventing the operator from touching the same while 30 rotating. This, combined with the disconnection of the dasher, renders it safe to use the extractor without any cover, although a cover 73 is preferably provided to prevent splashing during the washing operation and the same may be left on 35 during the extraction if desired. This splash-band is described and claimed in my application Serial Number 342,520 above mentioned.

In Figs. 6, 7, 8 and 9 of this application I have shown the machine illustrated and claimed in my 40 application Serial Number 694,899, above mentioned. This machine comprises a casing having a side wall 1* and bottom wall 2*, supported on a suitable frame and having a vertical central sleeve 3* in which is journaled a vertical hollow 45 shaft 15* in which, in turn, is journaled an inner shaft 17*. Operatively secured to and carried by the upper end of the shaft 15* is the hollow hub 4* of a container having a side wall 8* formed as a surface of revolution coaxial with said hub. 50 The bottom of this container is as before made hollow with spaced annular bracing parts, the upper at least thereof being frusto-conical in shape, and the side wall is formed with liquid apertures 80 near the top thereof, although the 55 lower part is substantially imperforate to prevent the escape of liquid. Above the apertures 80 an inwardly-tapering safety-guard 7* is provided.

Carried by the upper end of the shaft 17* is the oscillatable-dasher 12* terminating about its 60 lower end in a downwardly-flaring conical disk 13* which closely overlies the flaring bottom of the container and formed on its exterior with dasher blades 14*.

The sleeve 3* is supported by attachment to a 65 hollow neck 20* carried by the supporting frame, and rotatably journaled on the shaft 17* beneath said sleeve is the hub 21* of a spiral gear 22* which meshes with companion spiral gear 23* carried by the horizontal drive-shaft 24*. Journaled to the frame on a level with the gear 22* is a spiral gear 33* connected by a pitman 36* to an oscillatable toothed member 37* pivoted on a 70 vertical axis at 38*.

75 Rigidly secured to the lower end of the shaft 75

17^a is a pinion 40^a adapted to mesh with the oscillatable member 37^a, and rigidly secured to the lower end of the hollow shaft 15^a may be the radially-slotted plate 81 by means of which motion is transmitted to said sleeve from the pinion 22^a through the friction disk clutch shown in Fig. 8 and constructed as follows:

The hub 21^a projects above the face of the gear 22^a and is radially slotted as at 82 for the reception of the inwardly-projecting fingers 83 of the annular metal disks 84 that are slidably applied over said hub. Interspersed between these disks are other annular disks 85 similar thereto except for the possession of outwardly-projecting fingers 86 instead of the inwardly-projecting fingers, these being slidably received in radial slots 87 formed in the depending annular lip of a freely-rotatable plate 88 which is journaled on a nut 89 threaded to the extremity 20 of the hub 21^a. With this arrangement it will be seen that alternate disks will at all times rotate with the hub, and the intermediate disks will at all times rotate with the plate 88, and that any friction between those disks will create 25 a tendency for those parts to rotate together. A limited degree of friction for this purpose is produced by some coiled springs 90 interposed between the gear 22^a and the nearest disk, these being located in apertures formed for the purpose in a flange 91 carried by said hub. Motion of the plate 88 is transmitted to the plate 81 by means of a finger 93 carried by the one and engaging the slots of the other.

Carried by the lower end of the shaft 17^a is a 35 thrust-bearing 50^a which rests on a stirrup 44^a, one end of which is pivoted at 95 to a frame member and the other end of which is articulated at 96 to a link whose upper end is attached to an arm 97 carried by a rock-shaft 98 provided with a hand-lever 99. In one position of said hand-lever the gear 40^a meshes with the oscillating member 37^a producing oscillatory movement of the shaft 17^a and the dasher attached thereto, the pin 93 being meanwhile disengaged so that 45 the container is at rest. In the other position of this lever the gear 40^a is disconnected from the member 37^a, it and the gear 22^a being elevated until the pin 93 engages the plate 81, whereupon the container acquires a gradually increasing 50 speed by way of the friction clutch, the dasher being meanwhile free to stand still or to move at will, depending only upon the friction between the two shafts and their related parts. The only substantial difference between the two 55 machines is that in the first described device the container is filled with washing liquid by lowering it into the liquid, while in the second device filling is accomplished by raising the liquid. For this purpose I have shown the hub 4^a as formed 60 with vertical flow-openings 100 and the sleeve 3^a as surrounded by a conduit 101 communicating therewith. Located at one end of the motor 60^a is a centrifugal pump 102 whose inlet is connected by a pipe 103 with the bottom of the casing and 65 whose outlet is connected by a pipe 104 with the conduit 101. In this way a continuous overflowing of liquid from the container 8^a is produced during the time that the mechanism is being driven by said motor through the belt 63^a. 70 The supporting frame of the first described device is preferably made of three vertical channel members 110 rigidly secured at top and bottom to horizontal angle-irons 111, the parts being spot-welded together to make a light and rigid 75 whole. Three of these uprights are preferably

employed, the side flanges 112 of the uprights being flared at an angle of 60°. The sides of the frame are then covered by flat sheet-metal panels 113 by which the mechanism is hidden, that panel which constitutes the front of the 5 housing being stamped out as shown at 114 in the form of a hemispherical boss to constitute the sector for the pedal and formed with a vertical slot 115 to permit the pedal movement.

However, a vertical cornered housing like this 10 has an awkward appearance and gives insufficient stability. Accordingly I affix to the lower end of each upright 110 a rigid outwardly projecting bracket 116 in which are mounted the 15 castors 117; and over each corner of the housing I attach a hollow slanting sheet-metal sham 118, which overlaps the fans of the panels 113 and affords a finished appearance at minimum cost. The lower margins of the panels 113 are extended beyond the uprights so as to prevent 20 the formation of any gap between it and the sham. The top of the housing is surrounded by a narrow skirt 121 hiding the top of the housing and of the shams and having an annular seating-ring 122 on which the casing rests, being secured in place by suitable bolts 123 and rubber washers 124. The bearings 30 heretofore mentioned are most conveniently carried by a bracket 125 secured to that upright 110 which is opposite the 30 pedal.

While I have described in detail the construction and mode of operation of two preferred forms of my inventive idea it will be understood that a great many constructions can be employed 35 without departing from my invention or losing its benefits and I therefore do not limit myself to the details herein illustrated and described except as the same are specifically recited in my several claims which I desire may be construed 40 broadly independently of limitations contained in other claims.

Having thus described my invention what I claim is:

1. In a laundry machine, in combination, a 45 casing, a container mounted therein for movement about a vertical axis, said container being supported solely from below and said casing and container both having axial working openings at the top, a centrally located dasher inside said 50 container with the marginal portions of said dasher being spaced a considerable distance from the side walls of said container, said dasher and container being independently rotatable about one and the same vertical axis, means for oscillating said dasher while said container is at rest, 55 means for rotating said container, and means for maintaining said dasher at rest during the rotation of said container.

2. In a laundry machine, in combination, a 60 casing, a container mounted therein for movement about a vertical axis, said container being supported solely from below and said casing and container both having axial working openings at the top, a dasher inside said container, said dasher and container being independently rotatable about one and the same vertical axis, means for raising and lowering said container into and out of liquid contacting position, means operative while said container is in its lowered position to 70 oscillate said dasher without moving said container, means operative while said container is elevated for rotating said container, and means for preventing movement of said dasher during rotation of said container.

3. In a laundry machine, in combination, a casing, an upright sleeve fixedly secured to the bottom thereof and rising above liquid level therein, a hollow shaft journaled in said sleeve, a second shaft journaled inside said hollow shaft, said shafts being movable each independently of the other, an upright rotatable container located inside said casing and secured to said hollow shaft, an oscillatable dasher located inside said container and secured to said second shaft, a driving element beneath said container, gearing for connecting said driving-element to said shafts selectively, said gearing comprising an oscillating element adapted to be connected solely to said second shaft and a rotating element adapted to be connected solely to said hollow shaft, and means for disconnecting said gearing from both of said shafts before connecting it to either of said shafts.
4. In a laundry machine, in combination, a casing, an upright sleeve fixedly secured to the bottom thereof and rising above liquid level therein, a hollow shaft journaled in said sleeve, a second shaft journaled inside said hollow shaft, said shafts being movable each independently of the other, a second sleeve movably surrounding said first sleeve and secured to said hollow shaft, an upright rotatable container carried by and coaxial with said second sleeve, a third sleeve movably surrounding said second sleeve and secured to said second shaft, said third sleeve having dasher blades, a driving element beneath said container, gearing for connecting said driving-element to said shafts selectively, said gearing comprising an oscillating element adapted to be connected solely to said second shaft and a rotating element adapted to be connected solely to said hollow shaft, and means for disconnecting said gearing from both of said shafts before connecting it to either of said shafts.
5. In a laundry machine, in combination, a casing, a container mounted for movement about a vertical axis inside said casing, a dasher mounted inside said container for movement about the same axis, a driving element located beneath said casing, operating gearing comprising an oscillating element and a rotating element operatively connected to said driving element, mechanism for connecting said gearing to said dasher and container selectively and preventing said gearing from being connected to said dasher and container simultaneously, said rotating element being connectible solely to said container and said oscillating element being connectible solely to said dasher, and means to hold said dasher stationary during the rotation of said extractor.
6. In a laundry machine, in combination, a casing, a container mounted therein for movement about a vertical axis, said container being supported solely from below and said casing and container both having axial working openings at the top, a dasher inside said container, said dasher and container being independently rotatable about one and the same vertical axis, means for raising and lowering said container into and out of liquid contacting position, means operative while said container is in its lowered position to oscillate said dasher without moving said container, and means operative while said container is elevated for rotating said container and for holding said dasher against rotation.
7. In a laundry machine, in combination, a casing, an upright sleeve fixedly secured to the bottom thereof and rising above liquid level therein, a hollow shaft journaled in said sleeve,
- a second shaft journaled inside said hollow shaft, said shafts being movable each independently of the other, an upright rotatable container located inside said casing and secured to said hollow shaft, an oscillatable dasher located inside said container and secured to said second shaft, a driving element beneath said container, gearing for connecting said driving-element to said shafts selectively, said gearing comprising an oscillating element adapted to be connected solely to said second shaft and a rotating element adapted to be connected solely to said hollow shaft, and means for axially moving said shafts for disconnecting said gearing from both of said shafts before connecting it to either of said shafts.
8. In a laundry machine, in combination, a casing, an upright sleeve fixedly secured to the bottom thereof and rising above liquid level therein, a hollow shaft journaled in said sleeve, a second shaft journaled inside said hollow shaft, said shafts being movable each independently of the other, an upright rotatable container located inside said casing and secured to said hollow shaft, an oscillatable dasher located inside said container and secured to said second shaft, a driving element beneath said container, gearing for connecting said driving-element to said shafts selectively, said gearing comprising an oscillating element adapted to be connected solely to said second shaft and a rotating element adapted to be connected solely to said hollow shaft, and means for axially moving said dasher and container for disconnecting said gearing from both of said shafts before connecting it to either of said shafts.
9. In a laundry machine, in combination, a casing, an upright sleeve fixedly secured to the bottom thereof and rising above liquid level therein, a hollow shaft journaled in said sleeve, a second shaft journaled inside said hollow shaft, said shafts being movable each independently of the other, a second sleeve movably surrounding said first sleeve and secured to said hollow shaft, an upright rotatable container carried by and coaxial with said second sleeve, a third sleeve movably surrounding said second sleeve and secured to said second shaft, said third sleeve having dasher blades, a driving element beneath said container, gearing for connecting said driving-element to said shafts selectively, said gearing comprising an oscillating element adapted to be connected solely to said second shaft and a rotating element adapted to be connected solely to said hollow shaft, and means for axially moving said shafts for disconnecting said gearing from both of said shafts before connecting it to either of said shafts.
10. In a laundry machine, in combination, a casing, an upright sleeve fixedly secured to the bottom thereof and rising above liquid level therein, a hollow shaft journaled in said sleeve, a second shaft journaled inside said hollow shaft, said shafts being movable each independently of the other, a second sleeve movably surrounding said first sleeve and secured to said hollow shaft, an upright rotatable container carried by and coaxial with said second sleeve, a third sleeve movably surrounding said second sleeve and secured to said second shaft, said third sleeve having dasher blades, a driving element beneath said container, gearing for connecting said driving-element to said shafts selectively, said gearing comprising an oscillating element adapted to be connected solely to said second shaft and a rotating element adapted to be connected solely to said hollow shaft, and means for axially moving said dasher and container for disconnecting said gearing from both of said shafts before connecting it to either of said shafts.

said hollow shaft, and means for axially moving said dasher and container for disconnecting said gearing from both of said shafts before connecting it to either of said shafts.

5 11. In a laundry machine, a casing, a container in said casing, an agitator located inside said container having a base portion closely adjacent to the container bottom with upstanding vanes, the marginal edge portions of which are spaced 10 a considerable distance from the side walls of said container and facing in a generally outward direction from the center thereof, a rotating member and an oscillating member located underneath said casing, shaft means working 15 through the bottom of said casing, and mechanism including said shaft means, effective with said agitator in its operative position for selectively connecting and disconnecting either said rotating member with respect to said container or 20 said oscillating member with respect to said agitator, but not otherwise, whereby said container is continuously rotated or said agitator is oscillated through an arc of less than 360°, said mechanism having provisions for maintaining said 25 agitator stationary while said container is connected to said rotating member and leaving said container free while said agitator is connected to said oscillating member.

12. In a laundry machine, an agitator, a container and a casing, located one inside the other in the order named, a rotating member and an oscillating member located underneath said casing, a fixed bearing member for said rotating member, shaft means working through said bearing member and the bottom of said casing for selectively connecting said oscillating member to said agitator and said rotating member to said container for operating said agitator and said container one independently of the other, and 30 manually controlled mechanism including said shaft means for raising and lowering said container and agitator for either disconnecting said agitator from said oscillating member and then connecting said rotating member to said container or for disconnecting said container from said rotating member and then connecting said oscillating member to said agitator.

13. In a combined washing and extracting machine, a rotatable extractor-container, washing means comprising an agitating device adapted for back-and-forth movement in said extractor-container, rotatable and back-and-forth moving mechanism for respectively driving said extractor-container and said washing means each independently of the other, said mechanism including a relatively fixed bearing member, a gear journaled thereon, a pair of shafts arranged one inside the other in said bearing member, said inner shaft being adapted for driving said washing means and said outer shaft being adapted for driving said extractor-container, and means operable with said washing means in place for selectively connecting said extractor-container and said washing means to said mechanism, said washing means being located in the central region of said container with its outermost marginal portions spaced inwardly a substantial distance from the side wall of the extractor-container so as to define a space outside the agitator for the reception of the articles being centrifuged during the normal operation of the machine whereby such articles will be in contact only with the extractor-container and thus will have no tendency to drive the agitating device.

14. In a combined washing and extracting ma-

chine, a rotatable extractor-container, washing means comprising an agitating device adapted for back-and-forth movement in said extractor-container, said washing means and said container being at all times free for relative movement with respect to each other, rotatable and back-and-forth moving mechanism for respectively driving said extractor-container and said washing means each independently of the other, said mechanism including a pair of shafts arranged one inside the other, said inner shaft being adapted for driving the agitating device of said washing means and said outer shaft being adapted for driving said extractor-container, and means operable with said washing means in place for selectively connecting said extractor-container and said washing means to said mechanism, said last-named means and mechanism including a gear journaled for movement on a fixed part of the machine and axially movable relatively thereto, a driving clutch element fixed to said gear, a cooperating driven clutch element fixed to rotate with one of said shafts and movable into engagement with said driving clutch element and resilient means working on said gear and driving element for maintaining said clutch parts in driving engagement, said washing means being located in the central region of said container with its outermost marginal portions spaced inwardly a substantial distance from the side wall of the extractor-container so as to define a space outside the agitator for the reception of the articles being centrifuged during the normal operation of the machine whereby such articles will be in contact only with the extractor-container and thus will have no tendency to drive the agitating device.

15. In a combined washing and extracting machine, a rotatable extractor-container, washing means comprising an agitating device adapted for back-and-forth movement in said extractor-container, rotatable and back-and-forth moving mechanism for respectively driving said extractor-container and said washing means each independently of the other, said mechanism including a pair of shafts arranged one inside the other, said inner shaft being adapted for driving the agitating device of said washing means and said outer shaft being adapted for driving said extractor-container, and means operable exteriorly of the machine with said agitating device in place for selectively connecting said extractor-container and said washing means to said mechanism, said last-named means and mechanism including a gear journaled for movement on a fixed part of the machine and axially movable relatively thereto, a driving clutch element fixed to said gear, a cooperating driven clutch element fixed to rotate with said shaft means and movable into engagement with said driving clutch element and resilient means working on said gear and driving element for maintaining said clutch parts in driving engagement.

16. In a combined washing and extracting machine, a rotatable extractor-container, washing means adapted for back-and-forth movement comprising a vaned agitator extending upwardly from the bottom part of said extractor-container, and rotatable and back-and-forth moving mechanism for respectively driving said extractor-container and said washing means each independently of the other, said mechanism including a relatively fixed bearing member, a gear journaled thereon and a pair of shafts arranged one inside

the other in said bearing member, said inner shaft being adapted for driving the vaned agitator of said washing means and said outer shaft being adapted for driving said extractor-container and means for connecting and disconnecting said outer shaft with respect to said gear, said agitator being located in the central region of said container with its outermost marginal portions spaced inwardly a substantial distance from the side wall of the extractor-container so as to define a space outside the agitator for the reception of the articles being centrifuged during the normal operation of the machine whereby such articles will be in contact only with the extractor-container and thus will have no tendency to drive the agitating device.

17. In a combined washing and extracting machine, a rotatable extractor-container, washing means comprising an agitating device adapted for back-and-forth movement in said extractor-container, rotatable and back-and-forth moving mechanism for respectively driving said extractor-container and said washing means each independently of the other, coaxial driving shafts for said extractor-container and said washing means, the outer of said shafts being adapted for driving said extractor-container, means operable with said washing means in place for selectively connecting said shafts to said mechanism, the agitating device of said washing means being located in the central region of said container with its outermost marginal portions spaced inwardly a substantial distance from the side wall of the extractor-container so as to define a space outside the agitator for the reception

tion of the articles being centrifuged during the normal operation of the machine whereby such articles will be in contact only with the extractor-container and thus will have no tendency to drive the agitating device, and means for maintaining said agitator stationary during the rotation of said extractor-container.

18. In a combined washing and extracting machine, a rotatable extractor-container, an oscillatable agitator in said extractor-container, rotatably and oscillatably moving mechanism for respectively driving said extractor-container and said agitator each independently of the other, said mechanism including a pair of shafts arranged one inside the other, said inner shaft being adapted for driving the agitator of said washing means and said outer shaft being adapted for driving said extractor-container, and means operable with said agitator in place for selectively connecting said extractor-container and said agitator to said mechanism, said agitator being located in the central region of said container with its outermost marginal portions spaced inwardly a substantial distance from the side wall of the extractor-container so as to define a space outside the agitator for the reception of the articles being centrifuged during the normal operation of the machine whereby such articles will be in contact only with the extractor-container and thus will have no tendency to drive the agitating device, and means for maintaining said agitator stationary during the rotation of said extractor-container.
